US0D1067787S

(12) **United States Design Patent** (10) **Patent No.:** **US D1,067,787 S**
(45) **Date of Patent:** **** Mar. 25, 2025**

(54) **TIMER**

(71) Applicant: **Fuzhou Bangshi Electronics Co., Ltd,**
Fuzhou (CN)

(72) Inventor: **Liuye Weng**, Fuzhou (CN)

(**) Term: **15 Years**

(21) Appl. No.: **35/520,073**

(22) Filed: **Nov. 1, 2023**

(80) **Hague Agreement Data**

Int. Filing Date: **Nov. 1, 2023**

Int. Reg. No.: **DM/235172**

Int. Reg. Date: **Nov. 1, 2023**

Int. Reg. Pub. Date: **Feb. 23, 2024**

(30) **Foreign Application Priority Data**

May 11, 2023 (CN) 202330275404.1
